[57] CLAIM

The ornamental design for a rotary lawn edger, trimmer or similar article, substantially as shown and described.

DESCRIPTION

FIG. 1 is a side elevational view of a rotary lawn edger, trimmer or similar article embodying our new design;
FIG. 2 is a front elevational view thereof;
FIG. 3 is a top plan view thereof;
FIG. 4 is a bottom plan view thereof; and
FIG. 5 is an isometric view thereof.
